OPTICAL ELECTROPHORESIS SCANNER

Jan A. Van den Broek, Ann Arbor, and George W. Toma, Dexter, Mich., assignors to Transidyne General Corporation, Ann Arbor, Mich.

Filed June 1, 1971, Ser. No. 149,133

Term of patent 14 years

Int. Cl. D24—01

U.S. Cl. D16—2

Fig. 3

FIG. 1 is a front elevational view of an optical electrophoresis scanner showing our new design;

FIG. 2 is a left side elevational view thereof; and

FIG. 3 is a front and right side perspective view thereof.

The rear, not shown, is substantially plain and unornamented.

We claim:

The ornamental design for an optical electrophoresis scanner, as shown and described.
